CASE FOR EMERGENCY EXIT LOCKS

Joseph M. Parriott, Westport, Conn., assignor to
Emhart Corporation

Filed July 5, 1962, Ser. No. 70,798

Term of patent 14 years

(Cl. D10—8)

FIG. 1

FIG. 4

FIG. 2

FIG. 3

FIG. 5

FIGURE 1 is an isometric view of a case for emergency exit locks embodying my new design.

FIGURE 2 is a front elevational view,

FIGURE 3 is a side elevational view taken from the right of FIG. 2.

FIGURE 4 is a top plan view; and

FIGURE 5 is a bottom plan view.

The dominant features of my design reside in the portions shown in solid lines.

I claim:

The ornamental design for a case for emergency exit locks, substantially as shown and described.
